(57) **CLAIM**

The ornamental design for an off-road vehicle body, as shown and described.

DESCRIPTION

FIG. 1 is a perspective view taken from a front, left side of an off-road vehicle body according to our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Throughout the Figures, where shown, the dashed broken lines shown in the drawings are for the purpose of illustrating portions of the article and form no part of the claimed design, and the dot-dash broken lines define the bounds of the claimed design and form no part thereof.
